[57] CLAIM

The ornamental design for a ski hanger, as shown and described.

DESCRIPTION

FIG. 1 is a front elevational view of a ski hanger showing my new design, the skis which are fragmentarily shown in broken lines are for illustrative purposes only; FIG. 2 is a top plan view thereof;

FIG. 3 is a bottom plan view thereof;

FIG. 4 is a side elevational view taken from the left of FIG. 1;

FIG. 5 is a side elevational view taken from the right of FIG. 1.
